UNITED STATES PATENT OFFICE.

JOHN V. WALSH, OF HAVERHILL, MASSACHUSETTS.

METHOD OF FINISHING HAT-BODIES.

1,152,387.

Specification of Letters Patent. Patented Aug. 31, 1915.

Application filed January 19, 1915. Serial No. 3,150.

To all whom it may concern:

Be it known that I, JOHN V. WALSH, a citizen of the United States, residing at Haverhill, Essex county, and State of 5 Massachusetts, have invented and discovered certain new and useful Improvements in Methods of Finishing Hat-Bodies, of which the following is a specification.

My said invention consists in an improved 10 method of finishing hat bodies, whereby a peculiar and attractive appearance is given to the hat, all as will be hereinafter more fully described and claimed.

The accompanying drawing illustrates an 15 ordinary hat buffing, or pouncing, machine, such as is used in common methods of finishing hat bodies, and which I also employ in my improved method.

In said drawing the portion marked A 20 represents the frame or support, B the shaft carrying the operating element, such as a buffing head, or emery wheel, C such element, D an arm carrying the support for the hat body while being operated upon, E 25 said support, shown in dotted lines, F a foot lever for manipulating said support, G a driving belt, and H a hat body in position for manipulation and treatment by the operating element under the manipulation of the 30 operator. All these features are of common form and arrangement, well understood in the art, and need no special description. In the face of the supporting head E a groove is formed in which is mounted a 35 cushion e, preferably a section of rubber hose covered by a cloth, thus affording a soft elastic support for the work.

In the practice of my invention, a felt hat body, prepared from either wool or fur felt 40 in the usual or any approved manner, is first treated by subjecting its surface to the action of a coarse abrasive material on the surface of the buffing or pouncing wheel, such as C, of the machine. In this treatment, the hat body under the manipulation of the operator is brought into contact with the abrasive surface and turned parallel with the edge of the body, or subjected to a treatment extending in a circular direction 45 around said body. Then it is subjected to similar treatment under the action of a fine abrasive material, or sandpaper, on the surface of the buffing wheel. It is then subjected to a treatment by the coarse sandpaper, but in a direction across the direction of the 50 first and second treatments, that is, the hat

body is manipulated over support E so as to bring its surfaces into contact with the wheel along lines running from the rim of the body to the crown. This treatment runs 60 the "grain" in the direction from the crown toward the rim of the hat, and is accomplished by holding the crown of the hat in the fingers and running the hat body over support E in the direction noted, across the 65 surface of the buffing wheel, by successive steps, until the entire circumference of the hat has been treated in this manner. This treatment produces a surface which is lustrous and silky in appearance, with the 70 fibers lying in the vertical direction in relation to the hat instead of horizontal. After this treatment, the hat body is lured, or subjected to treatment by a felt wheel, or a wheel having a felt buffing surface, in the 75 same direction as the last direction in which it was treated by the coarse sandpaper, that is, up and down. This treatment smooths and irons out, or polishes, the surface of the hat, giving it a lustrous and silky finish. It 80 is then ready to be shaped, which is accomplished by the usual, or any approved process, and during which the luster of the 85 finish will be impaired to some extent. After the shaping is completed and the hat dried it is again subjected to the action of the felt or "luring" wheel and the fibers smoothed down from the crown of the hat to the rim, and the luster and silk finish restored. The hat is then ready for trimming 90 and packing. The finish thus secured, is of a silky, lustrous appearance, with the grain running vertically, and I have termed it a velour bright finish.

Having thus fully described my said invention, what I claim as new and desire to secure by Letters Patent, is:

1. The method of finishing hat bodies which consists in subjecting a felt hat body to a circular treatment by coarse abrasive 100 material, then subjecting it to a similar treatment in the same direction by fine abrasive material, then subjecting it to a treatment by coarse abrasive material in a direction across the direction of the other 105 treatments from the rim to the crown, then subjecting it to a smoothing and "luring" treatment by a felt wheel in a direction from the rim to the crown, then shaping, and then subjecting to another treatment by 110 the felt wheel, substantially as set forth.

2. The method of finishing hat bodies

which consists in treating a felt hat body first with abrasive material in a circular direction, then in a direction from the rim to the crown, then subjecting it to treatment by a luring wheel in a direction from the rim to the crown, substantially as set forth.

In witness whereof, I have hereunto set

my hand and seal at Washington, D. C. this 14th day of January, A. D. nineteen hundred and fifteen.

JOHN V. WALSH. [L. S.]
